UNITED STATES PATENT OFFICE.

JOSEPH H. JACKSON, OF CLANTON, ALABAMA, ASSIGNOR OF ONE-THIRD TO FRED L. BLACKMAN, OF ANNISTON, ALABAMA.

RANGE-FINDER.

1,261,236.

Specification of Letters Patent.

Patented Apr. 2, 1918.

Application filed July 17, 1917. Serial No. 181,144.

To all whom it may concern:

Be it known that I, JOSEPH H. JACKSON, a citizen of the United States, residing at Clanton, in the county of Chilton and State 5 of Alabama, have invented a new and useful Range-Finder, of which the following is a specification.

The present invention appertains to range finders, and aims to provide a novel and improved yet comparatively simple and inexpensive device for readily and accurately determining the distances to various objects, for use by surveyors, for military and naval operations to determine the range, and the 15 like.

The invention has for its object the provision of a range finder which will, by simply bringing the sights in line with the object, automatically indicate the range, so 20 that no mathematical calculations or skill on the part of the operators is necessary.

With the foregoing and other objects in view, which will appear as the description proceeds, the invention resides in the combination and arrangement of parts and in the details of construction hereinafter described and claimed, it being understood that changes in the precise embodiment of the invention herein disclosed can be made within 30 the scope of what is claimed, without departing from the spirit of the invention.

The invention is illustrated in the accompanying drawing, wherein:

Figure 1 is a plan view of the range finder. 35 Fig. 2 is an enlarged sectional detail on the line 2—2 of Fig. 1, portions being broken away.

In carrying out the invention, there is provided a suitable stock 1, which is preferably mounted upon a suitable base 2, one 40 end of the stock being pivoted, as at 3, to the base. The stock is provided at its other end with an arm 4 extending at a right angle therefrom and carrying suitable sighting means 5, such as a telescopic sight when great accuracy is desired, although ordinary notch and bead sights or the like can be used for shorter ranges.

It is preferable to provide means for moving the stock 1 to bring the sight 5 in line with the object, such as the provision of a worm 6 engaging an arcuate series of teeth 7 carried by the base, the spindle 8 of the worm being journaled in a bearing 9 carried by the stock, and having a knob 10

adapted to be rotated manually, whereby to swing the stock about the pivot, thus enabling the operator to readily bring the sight 5 in line with the object.

The stock 1 is provided at its pivoted end 60 with a second arm 11 extending at a right angle therefrom, preferably in the same direction as the arm 4, and a slide 12 is movable longitudinally on the arm 11, being provided with an upstanding stem 13 that can 65 be used as one member of a sight, there being suitable sighting means 14, such as a telescopic sight, or the like, at the pivot 3. The arm 11 is suitably graduated, as at 21, according to the distance between the sights 70 5 and 14, whereby when the sight 5 is brought on the object, and the slide 12 moved to bring the sight member 13 in a line between the sight 14 and object, the slide 12 will indicate on the graduations 21, 75 the distance to the object from the range finder, according to the principles of trigonometry. It is evident that the farther away the object is, the slide 12 will have to be moved a proportional distance farther 80 along the arm 11 away from the stock 1. The line 23 along which the sight 5 axis extends, is always a predetermined distance from the pivot 3, and the angle between the stock and line 23 is always a right angle, 85 while the line 22 of the sights 13 and 14 is variable in its angle with the stock and line 23 as the slide 12 is slid outwardly and inwardly. The graduations 21 are, therefore, in proportion to the length of the stock or 90 the distance between the pivot 3 and line 23, and said graduations may represent multiples of said fixed distance.

It is preferable to provide some means for readily moving the slide 12 and bringing 95 the sights 13 and 14 in line with the object conveniently, especially for accurate work when the object is a considerable distance off. Thus, the sight or telescope 14 can be mounted on a beam 15 engaging the pivot 3 to 100 swing thereon, the sight 14 extending longitudinally of the beam on the line 22, and said beam having one arm extending over the arm 11 and provided with a longitudinal slot 16 receiving the member 13. Thus, as 105 the slide 12 is moved back and forth, the member 13 in working in the slot 16, will swing the beam 15 to automatically keep the member 13 in line between the object and sight 14. It is, therefore, only necessary to 110

move the slide 12. This can be accomplished by the provision of a screw 17 extending along the arm 11 and carried by suitable bearings 18 on the stock 1 and arm 11, the slide 12 having a nut 19 threaded upon the screw, and the screw having a knob 20 to be manually rotated for moving the slide 12 with the nut 19.

When extreme simplicity is desired, for short range work, the base 2, beam 15, and parts 6, 7, 8, 9, 10, 17, 18, 19 and 20 can be eliminated. The slide 12 can then be moved by hand, and ordinary sights can be used in place of the telescopic sights 5 and 14, the sight 14 being located at the point where the pivot 3 is along the line of the outer edge of the arm 7, while the sight member 13 is offset inwardly from said line.

It is also possible to equip the slide 12 with a plurality of sight members. An additional member 13' is illustrated with which the beam 15 can be engaged, the arm 11 having a corresponding additional set of graduations 21' to be read when the member 13' instead of the member 13 is used. Thus, the member 13' can be used for short ranges, while the member 13 can be used for long ranges.

The range finder can be readily used with a moving object, since one operator can keep a sight 5 in line with the object, by the manipulating knob 10, thus swinging the stock 1 without disturbing the operator looking through the sight 14. The second operator

can, by rotating the knob, 20, keep the sight 14 on line with the object, the slide 12 being moved back and forth. Thus, the slide 12 will continually indicate the range, even though it changes, when both sights are kept on the object.

Having thus described the invention, what is claimed as new is:

1. A range finder including two sighting means, one being adjustable angularly with respect to the other to focus upon an object in line with the other, a member movable with the adjustable sighting means, a fixed graduated arm arranged at an angle to said movable member, and a slide movable along the graduated arm and carrying a sighting element movably engaging and adapted to shift the movable member angularly.

2. A range finder embodying a stock, two sighting means carried thereby one including a slide, the stock having an arm along which said slide is movable, the slide having a plurality of sighting members, and the arm having different sets of graduations for the sight members to indicate the range.

In testimony that I claim the foregoing as my own, I have hereto affixed my signature in the presence of two witnesses.

JOSEPH H. JACKSON.
